UNITED STATES PATENT OFFICE.

TOBIAS L. CRANE, OF TYBONE, NEW MEXICO.

PULP-FILTER.

1,268,935.

Specification of Letters Patent. Patented June 11, 1918.

Application filed April 5, 1917. Serial No. 160,043.

To all whom it may concern:

Be it known that I, TOBIAS L. CRANE, a citizen of the United States, residing at Tyrone, in the county of Grant and State 5 of New Mexico, have invented certain new and useful Improvements in Pulp-Filters; and I do hereby declare the following to be a full, clear, and exact description of the invention, such as will enable others 10 skilled in the art to which it appertains to make and use the same.

This invention relates to improvements in a pulp filter of the type employing a tank or casing having a foraminous drum of the 15 suction type and airlifts and pneumatic agitators and has for one of its objects the provision of an agitator, which obviates the use of airlifts and pneumatic agitators, which have proven to be impractical, owing 20 to their becoming clogged or stopped up, causing the unrefined pulp to back against the drum and render the device inoperative.

Another object of this invention is to provide the agitator so located in the casing 25 or tank with respect to the drum that the pulp will be kept thoroughly agitated and prevented from backing against the drum hindering the operation of the same.

A further object of this invention is to 30 provide the agitator of arcuate formation so that the same will conform to the contour of the drum and which will prevent the backing of pulp against the drum.

A still further object of this invention is 35 the provision of a pulp filter attachment of the above stated character, which shall be simple, durable and efficient, and which may be manufactured and sold at a comparatively low cost.

With these and other objects in view, as 40 will become more apparent as the description proceeds, the invention consists of certain novel features of construction, combination and arrangement of parts as will 45 be hereinafter more fully described and claimed.

For a complete understanding of my invention, reference is to be had to the following description and accompanying drawings, in which:

Figure 1 is an end elevation of a pulp filter constructed in accordance with my invention,

Fig. 2 is a vertical sectional view of the 55 same,

Fig. 3 is a transverse sectional view of

the device illustrating the location of the agitator, and

Fig. 4 is a plan view of the agitator.

In pulp filters of the type employing the 60 casing having the foraminous suction drum and pneumatic agitators and lifts, it has been found that the pulp in the unrefined state which is within the casing or tank works its way through the stuffing boxes, 65 cutting out the packing which necessitates the discontinuance of operation for a period or considerable length in order to repack the stuffing boxes and also the pulp becomes heavy or contains coarse material, 70 causing the pulp to work its way into the pneumatic agitator and air lifts causing them to become clogged and render the device inoperative. When the agitator becomes inoperative, the pulp backs against 75 the foraminous drum and grips the same, thus causing a great increase in the power to drive the filter. If at this point, attention is not given to the accumulation of pulp within the casing or tank, the strain 80 on the machine becomes so great as to break the bearings of the driving construction of the device. To overcome the above objections to pulp filters of well known construction now upon the market, I have provided 85 a novel type of machine, which readily overcomes the aforementioned objections, and which will be hereinafter clearly described.

A substantially semi-circular tank 1 has 90 bearings 2, formed thereon, in which is journaled, a shaft 3 carrying a foraminous drum 4 of the suction type. The suction may be created within the foraminous drum 4 in any well known manner. The shaft 3 is driven 95 by any suitable motor power connected to the pulley 5 for the purpose of rotating the foraminous drum 4.

The pulp in an unrefined state may be administered to the tank in any well known 100 manner and upon rotation of the foraminous drum 4, the pulp will adhere to the periphery thereof owing to the suction created therein. A scraper 6 is carried by the casing or tank 1 and is adapted to remove the 105 pulp which has adhered to the periphery of the drum 4 as the same slowly rotates and deposits the same upon a suitable apron or conveyer, (not shown) by way of a chute 7.

A pair of arcuate shaped and relatively 110 spaced members 8 are connected together by members 9, which are constructed from

angle iron as clearly shown in Fig. 3. Upwardly and inwardly converging arms 10 are formed upon the arcuate shaped members 8 and to journals 11, which are rotatably mounted upon the bearings 2. Upwardly extending arms 12 are formed upon the journals 11 and have their upper free ends connected together by a bar 13. Rods 14 are journaled upon the rod 13 and are pivotally connected to crank arms 15 carried by the ends of a drive shaft 16. The drive shaft 16 is rotatably supported by standards 17 and has secured thereon, a pulley 18, which may be connected to any suitable motor power for the purpose of rotating the drive shaft 16, which causes the crank arms 15 to oscillate the arcuate shaped members within the tank or casing 1. The arcuate shaped members being connected by the members 9 provides a very efficient agitator, which will freely oscillate within the tank or casing 1 at a point below the lowest periphery of the foraminous drum, thus preventing the unrefined pulp within the tank or casing from banking against the drum and rendering the same inoperative. The members 9 being constructed from angle iron provide agitating strips for the agitator, which will thoroughly mix and agitate the unrefined pulp.

From the foregoing description taken in connection with the accompanying drawings, it will be noted that a novel form of agitator has been provided, which will obviate the use of the ordinary air lifts, pneu-

matic agitators and other types of mechanical agitators, and which will efficiently operate under all conditions, preventing the accumulation or banking up of unrefined pulp within the casing or tank.

While I have shown and described the preferred embodiment of my invention, it will be understood that minor changes in construction, combination and arrangement of parts may be made without departing from the spirit and scope of the invention as claimed.

Having thus described my invention, what I claim is:

A pulp filter comprising a casing, a suction drum, bearings formed on said casing and rotatably supporting said drum, a pair of arcuate shaped members disposed in said casing, upwardly and inwardly extending arms formed on said members, journals formed on said arms and rotatably supported by said bearings, a plurality of angle iron members connecting the arcuate shaped members and having their apexes disposed adjacent the drum to remove pulp therefrom, and means oscillating the arcuate shaped members.

In testimony whereof I affix my signature in presence of two witnesses.

TOBIAS L. CRANE.
